US00D532366S

(12) **United States Design Patent** (10) Patent No.: **US D532,366 S**
Koizumi (45) Date of Patent: **** Nov. 21, 2006**

(54) **COMBINED CHARGER AND TRANSMITTER
FOR HEADPHONE**

(75) Inventor: **Shiki Koizumi**, Tokyo (JP)

(73) Assignee: **Sony Corporation**, Tokyo (JP)

(**) Term: **14 Years**

(21) Appl. No.: **29/234,426**

(22) Filed: **Jul. 19, 2005**

(30) **Foreign Application Priority Data**

Mar. 31, 2005 (JP) D2005-009783

(51) **LOC (8) Cl. 13-02**

(52) **U.S. Cl. D13/108; D14/155**

(58) **Field of Classification Search** D13/107-110,
D13/118-119, 184; D14/155, 251, 253, 432,
D14/434; 320/107-115
